Primary Examiner — John R Yeh(74) *Attorney, Agent, or Firm* — Hoffmann & Baron, LLP(57) **CLAIM**

The ornamental design for a remote control, as shown and described.

DESCRIPTION

FIG. 1 is a top front perspective view of a remote control showing my new design;

FIG. 2 is a top plan view thereof;

FIG. 3 is a right side plan view thereof;

FIG. 4 is a left side plan view thereof;

FIG. 5 is a front plan view thereof;

FIG. 6 is a back plan view thereof; and,

FIG. 7 is a top rear perspective view thereof.

The bottom view forms no part of the claimed design.

The portions shown in broken line form no part of the claimed design.

1 Claim, 7 Drawing Sheets(56)
